UNITED STATES PATENT OFFICE.

HARRIE A. BALLARD, OF BOSTON, MASSACHUSETTS, ASSIGNOR TO UNITED SHOE MANUFACTURERY CORPORATION, OF PATERSON, NEW JERSEY, A CORPORATION OF NEW JERSEY.

CHANNELING MACHINE.

Application filed August 15, 1923. Serial No. 657,526.

This invention relates to channeling machines. As herein illustrated, the invention is embodied in a power-operated machine for channeling insoles for welt shoes. Many 5 features of the invention, however, are adapted for embodiment in machines for performing channeling or similar operations upon other kinds of work such, for example, as soles for turn shoes.

10 In a co-pending application, Serial No. 421,485, filed Nov. 3, 1920, by the present inventor, there is disclosed a channeling machine comprising a knife reciprocable in the line of feed of the work and arranged to cut 15 upon its backward stroke, a presser foot movable with the knife for gaging the depth of the cut, a primary feed device for feeding the work against the knife while the knife is moving backwardly to cut the work, 20 and a secondary feed device for imparting an auxiliary feed movement to the work to advance the work with the knife during the forward or non-cutting stroke of the knife.

One object of the present invention is to 25 provide an improved and simplified channeling machine in which the work is fed while the cutting means is operating and an additional feed movement is imparted to the work while the cutting means is inoperative 30 to cut the work.

With this object in view, an important 35 feature of this invention consists in the provision, in a machine of the class described, of feeding means intermittently operative to feed the work, cutting means movable opposite to the direction of feed to cut the work while said feeding means is operative and movable to starting position while said feeding means is inoperative, and means con- 40 stantly in engagement with the work for imparting an additional feed movement to the work during the movement of the cutting means to starting position. More specifically, and as embodied in the illustrated ma- 45 chine, this feature of the invention comprises a knife reciprocable in the line of feed of the work and arranged to cut upon its backward stroke, a main or primary feed- 50 ing means for feeding the work against the knife while the latter is moving backwardly to cut the work, and a presser foot which functions in a well-known manner during the backward or cutting stroke of the knife to gage the depth of the cut, and which is

constructed and arranged to impart an aux- 55 iliary feed movement to the work to advance the work with the knife during the forward or non-cutting stroke of the knife. By thus utilizing the presser foot for feeding 60 the work while the primary feeding means is inoperative and the knife is returning to its starting position, the employment of additional mechanism for feeding the work at this time is avoided and the construction of the machine is simplified to a 65 material extent.

In the illustrated embodiment of the invention, there is provided a channeling knife for cutting obliquely into the upper 70 face of a sole to form a channel and an inner lip, an edge-slitting knife for cutting inwardly from the sole edge to form an outer lip and a feather, and also a vertically dis- 75 posed knife associated with the edge-slitting knife for trimming the outer lip. Each of these knives is reciprocated in the line of feed and arranged to cut upon its backward stroke. In order further to simplify the construction and mode of operation of the 80 machine, provision is made for moving all of these knives in unison, and a single feed device is employed to effect the main or primary feed movement of the work, i. e., to advance the work during the concurrent 85 backward cutting strokes of the knives.

The means which is preferably employed 90 for this purpose comprises a single four-motion feed dog, the feeding stroke of which is timed to concur with the cutting strokes 95 of the knives. Two presser feet are pro- 100 vided, one of which is associated with the channeling knife and the other with the edge-slitting knife. These presser feet are arranged to move forwardly and backwardly and to yield vertically in unison with the knives. On the backward or cutting strokes of the knives the presser feet slide freely over the surface of the work and function in the well-known manner to gage the depth 105 to which the knives penetrate the work. The presser feet are so constructed that upon the forward or non-cutting strokes of the knives, and the concurrent return or idle movement of the feed dog, the presser feet bite into the work and feed the work along 110 with the knives. While it is preferred to employ two presser feet for feeding the work as above described, satisfactory results

can be obtained if only one presser foot is constructed and arranged to perform a feeding function and accordingly the invention is not limited to the use of a pair of presser feet for this purpose. Nor is the invention limited to the use of a presser foot having the usual gaging function as the means for imparting the auxiliary feed movement to the work. In the illustrated machine, as in 5 the machine of the hereinbefore mentioned co-pending application, the auxiliary feed movements are imparted to the work during the return or non-cutting strokes of the knives in order that the machine shall be enabled, at each successive cutting operation, 10 to make a cut the length of which is substantially equal to the distance travelled by the knife while it is cutting the work plus the distance through which the work is advanced 15 at each feed stroke of the primary feeding means or feed dog. In the drawings, the mechanism for horizontally reciprocating the feed dog has been designed to move the latter through a feed stroke somewhat longer 20 than the stroke of the knives and presser feet, and provision has been made for varying the relation between the path of the feed dog and the plane of the work table, so that the desired length of feed movement may 25 be derived from the feed dog regardless of variations in the thickness, density, or other characteristic of the work.

Another object of the invention is to insure the performance of superior channeling or cutting operations around the toe or other more or less sharply curved portion of the sole margin.

To this end, provision is made for varying the length of stroke of both the main and 40 the auxiliary feed devices. Preferably the stroke of the cutting means will also be varied at the same time. By thus varying the length of stroke of the feed devices and of the cutting means, the sole is enabled 45 to be swung or manipulated more readily to facilitate channeling around the toe. In the illustrated machine, the arrangement is such that the feed strokes and cutting strokes may 50 be shortened simultaneously and proportionately at the will of the operator upon the depression of a foot treadle or other control device and lengthened automatically and 55 concurrently upon the release of the treadle. Preferably also the strokes of both the main and the auxiliary feed devices and the 60 strokes of the cutting means are derived from actuators each of which has a constant throw, and the means for shortening the feed strokes and the cutting strokes accomplishes its purpose by utilizing portions only 65 of the throws of the actuators and is capable of nullifying the throws of the actuators entirely. Provision is also made in the illustrative machine whereby, when the throw of the actuator for the main feed de-

vice has been entirely or nearly nullified, said device will automatically be prevented from moving into engagement with the work at each successive operation of its actuator, thus further facilitating the swinging of the sole at the toe by causing the sole to be entirely clear of the main feed device so long as the latter has no work feeding movement.

The invention further consists in the features of construction and in the combinations and arrangements of parts hereinafter described and claimed, the advantages of which will be apparent to those skilled in the art.

The various features of the invention will be best understood from a description of the preferred embodiment thereof, illustrated in the accompanying drawings, in which:—

Fig. 1 is a view, in front elevation, of the improved channeling machine;

Fig. 2 is a side elevational view thereof;

Fig. 3 is a detail view showing the knives and illustrating the manner in which they operate upon the work;

Fig. 4 is a top plan view of the machine;

Fig. 5 is a view, partially in plan and partially in section, of the front portion of the machine, various parts being broken away to reveal certain structural features of the machine;

Fig. 6 is a front elevational view, on an enlarged scale, of the greater portion of the machine, certain parts being removed or broken away and a portion of the supporting structure being shown in section;

Fig. 7 is a detail sectional view taken along the line 7—7 of Fig. 6, and showing particularly the manner in which the channeling knives are mounted;

Fig. 8 is a sectional view of the machine taken substantially along the line 8—8 of Fig. 6;

Fig. 9 is a detail view, partially in section on the line 9—9 of Fig. 8, showing particularly the mounting of the edge-slitting and lip trimming knives and the associated presser foot;

Fig. 10 is a sectional view of the machine taken substantially along the line 10—10 of Fig. 6;

Fig. 11 is a view, in horizontal section, taken substantially along the line 11—11 of Fig. 1;

Fig. 12 is a detail perspective view showing the edge-slitting knife, the lip trimming knife and the presser foot associated therewith, together with the block upon which these parts are mounted;

Fig. 13 is a detail perspective view showing the channeling knife, the associated presser foot and the block upon which they are mounted;

Fig. 14 is a view, partially in plan and

partially in section on the line 14—14 of Fig. 2, certain parts being broken away for purposes of illustration; and

5 Figs. 15 and 16 are detail sectional views taken substantially along the lines 15—15 and 16—16, respectively, of Fig. 14.

Referring to the drawings, the machine therein shown comprises, in general, a frame or head 20 upon which the various operating instrumentalities are mounted; a freely rotatable work table or support 22 across which the work is fed while being operated upon; an edge gage 24 against which the work is held by the operator; a chamfer 15 knife 26 which is immovable in the direction of work feed and which functions to bevel the lower corner of the sole edge; a channeling knife 28 for forming the inner lip; an edge-slitting knife 30 for forming the outer 20 lip and the feather; a lip trimming knife 32 associated with the edge-slitting knife; presser feet 34 and 36 associated with the channeling knife and edge-slitting knife respectively; a horizontally reciprocating slide 25 or carriage 38 upon which is mounted the channeling, edge-slitting and lip trimming knives, and the presser feet; a four-motion feed dog 40; a second horizontally-reciprocating slide or carriage 42 which carries the feed dog; a main shaft 44; mechanism including two eccentrics 46 and 48 on the main shaft for operating the slides 38 and 42 simultaneously in opposite directions; and means including a third eccentric 50 on the 30 main shaft for moving the feed dog vertically into and out of feeding engagement with the work. For convenience of description the expression "channeling knives" will be adopted hereinafter to designate collectively the channeling knife 28 and the edge-slitting knife 30.

The frame or head 20 of the machine is supported at a convenient height for the operator by means of a suitable standard 54 having a flanged upper end 56 which is bolted, or otherwise rigidly secured, to the lower portion of the head. The main shaft 44, which carries the eccentrics for operating the reciprocating channeling knives and the feed dog, extends horizontally from the front to the rear of the machine and is journaled in bearings 58 in the upper portion of the head 20, said bearings being provided with suitable bushings 60. At its rear extremity, the shaft 44 is provided with a driving pulley 62 which may be connected with a suitable source of power. The channeling knife 28, the edge-slitting knife 30 and the lip trimming knife 32 are reciprocated in unison in the line of feed of the work by means of the slide 38 on which they are mounted and these knives are arranged to cut the work upon their backward strokes. The slide 38 which carries the above-mentioned parts and the slide 42 which carries

the feed dog 40 are located side by side in a portion of the head 20 which overhangs the feed table 22 and these slides are operated by the eccentrics 46 and 48, respectively, as hereinbefore stated. The eccentrics 46 and 70 48 are disposed with their centers located at diametrically opposite points to cause the slides 38 and 42 to move simultaneously in opposite directions so that the channeling knives will be moved opposite to the direction of feed to cut the work while the work is being fed forwardly against the knives by the feed dog. 75

While being operated upon, the work rests upon the work table 22. The work table 22 is circular in plan view and its periphery closely surrounded by a wall 64 (Figs. 8 and 14) having a cylindrical inner surface and an upper edge which is substantially flush with the upper face of the table and which co-operates therewith to afford a smooth, flat supporting surface for the work. The wall 64 is formed upon a slide 66 which is adjustable transversely of the line of feed of the work, the slide 66 being mounted for 80 this purpose upon a stationary horizontal work-table support 68 (Figs. 1 and 2) which projects forwardly from the base of the head 20. The work-table support 68 extends between flanges 70 which depend from opposite sides of the slide 66 and are arranged to bear against the corresponding sides of the work-table support to prevent lateral displacement of the slide. 85

To lessen frictional resistance to the feeding of the work, the work table 22 is mounted to turn freely within the enclosing wall 64. To this end, the work table is axially bored to provide a bearing socket 72 (Fig. 8) for a post 74 which rises from the base of the work-table slide 66 in co-axial relation to the inside of the wall 64. The work table rests upon an anti-friction bearing which may comprise hardened steel rings or washers 76 and 78, and a series of balls 80 100 that are confined in a cage 82 and are interposed between the rings 76 and 78. The side of the work table 22 is peripherally cut away or recessed, as shown at 84 in Fig. 8, to reduce its area of bearing surface in engagement with the wall 64. By thus recessing the table 22, bearing shoulders 86 and 88 are formed which engage the inner side of the wall 64 and serve, in conjunction with the post 74 and the bearing socket 72, to hold the 105 table against lateral vibration. The upper side wall of the peripheral recess 84 in the work table is beveled, as shown at 90, to reduce to a minimum the area of the bearing shoulder at the top of the table and further to provide clearance for the chamfer knife, 26, as will hereinafter appear. The anti-friction bearing supports the weight of the work table and receives the end thrust thereof while the work is being operated upon. 110

The edge gage 24 is rigidly secured to the rear of the cylindrical wall 64 by means such as the bolt 92 (Fig. 8) and projects above the plane of the work table to engage 5 the edge of the sole so as to determine the location of the channel cuts relatively to the sole edge, and thus to determine the width of the feather. In order that the width of feather may be varied upon different soles 10 or upon different portions of the margin of a sole, provision is made for varying the location of the edge gage relatively to the channeling knives and transversely of the line of feed. This is accomplished by adjusting the work-table slide 66 horizontally 15 upon the slide support 68.

The means for adjusting the work-table slide 66, to obtain the desired relative location of the channeling knives and the edge 20 gage, comprises a bell-crank lever 98, best shown in Fig. 14. The bell-crank lever 98 is pivoted for horizontal movement upon a bolt 100 and is provided with a relatively short cam arm 102 and a relatively long 25 operating arm 104. The pivot bolt 100 is secured to a segmental plate 106 which is rigidly secured, by means of screws 108, to the base of the head 20. The outer extremity of the long lever arm 104 is shaped to 30 provide an operating handle 110, and the segmental plate 106 and the handle 110 are provided with interengaging locking devices for maintaining the bell crank lever 35 98 in locked position at several points of its swinging movement so as to provide for a corresponding number of predetermined 40 adjustments of the work table, and consequently of the edge gage, relatively to the channeling knives, as will be explained 45 more fully hereinafter. The cam arm 102 of the bell-crank lever 98 is formed with a cam slot 112 (Figs. 2 and 14) adapted to receive a cam roll 114 carried by a stud 116 which depends from a rearward extension 50 118 of the work-table slide 66 and projects through a slot 120 in the slide support 68.

The hereinbefore mentioned interengaging 55 devices for securing the bell-crank lever 98 in locked position at several points of its swinging movement comprise a latch which is carried by the lever 110 and is indicated by the general reference numeral 122, and a series of notches 124, 126 and 128 which are formed in or by means of adjustable parts associated with the segmental plate 106 in a manner to be hereinafter described.

The latch 122 comprises two levers 130 and 132 (Figs. 1 and 16) which are pivoted together intermediate their ends by means of a pin 134. One end of the lever 130 is pivoted at 136 to the handle 110 of the bell-crank lever 98 and the corresponding end of the latch lever 132 is shaped to enter 60 the several notches 124, 126 and 128. The

opposite ends of the latch levers 130 and 132 are shaped to form handles 138 and 140, respectively, to be manipulated by the fingers of the hand which grasps the handle 110 of the lever for adjusting the work 65 table. Ears 142 depending from the handle 110, at opposite sides of the lever 130, serve to guide the latter and to reinforce it against the thrust of the work when the lever 98 is locked in one of its several adjusted positions. The latch levers 130 and 132 are normally maintained in the relative 70 positions in which they appear in Fig. 16 by means of a spring 144 which is interposed between the handles 138 and 140 and holds the inner arm of the lever 132 against a portion of the lever 130. The holding engagement of the latch 122 with one or another of the notches 124, 126 and 128 is maintained by means of a spring 146 which is interposed between the handle 110 and the lever 130. The relation of the pivots 134 and 136 to the segmental plate 106 is such that the handle 138 may be lifted to disengage the latch from the co-operating 75 notch in the segmental plate, and the relation further is such that the handle 140 may be manipulated to depress the opposite end of the latch lever 132 below the plane of the segmental plate 106 for a purpose to be 80 hereinafter described.

Provision is made whereby the positions of the several notches engaged by the latch 122 may be shifted relatively to the pivot 100 of the bell-crank lever 98 to provide for 85 various predetermined relative adjustments of the edge gage and channeling knives. To this end, as best shown in Figs. 14 and 16, the central notch 124 is formed in a forwardly projecting portion 150 of a segmental slide 152 that is adjustably secured to the front of the segmental plate 106. The segmental portion of the slide 152 is located in a segmental guideway 154 in the plate 106, the guideway being formed between a shoulder 105 and two lugs 155, 155 which project upwardly from the plate 106 at opposite sides of the portion 150 of the slide 152. The slide 152 is adapted to be adjusted 90 longitudinally in its guideway 154 to vary the radial location of the central notch 124, and thus to vary the relative adjustment of the edge gage and the channeling knives when the latch 122 is engaged in said central notch. A clamping screw 160 which is threaded into the plate 106 is provided with a head which overlaps a portion of the segmental slide 152 and which serves to lock 95 this slide in adjusted position when the screw is tightened. The notches 126 and 128 are formed between shoulders on the forwardly projecting portion of the slide 152 and the adjacent opposed ends of two blocks 156 and 158. The blocks 156 and 158 are adjustably secured to the peripheral face 100

of the segmental plate 106 by means of screws 162 the shanks of which extend through longitudinal slots 164 in the blocks. The slots 164 permit adjustment of the blocks toward and from the adjacent shoulders on the slide 152. When the location of the central notch 124 is changed, the blocks 156 and 158 may be adjusted to widen one of the notches 126 and 128 to enable it to receive the co-operating portion of the latch 122, and to shorten the other of said notches to prevent play between the latch and the sides of the notch. Thus the radial positions of the three notches 124, 126 and 128 with respect to the pivotal axis of the bell-crank lever 98 may be varied at will by the operator. By grasping the handles 110 and 138 and moving them toward one another, the latch 122 will be lifted from the notch which it engaged and the lever 98 may then be moved freely in one direction or the other to adjust the slide 66 and the work table. Obviously this adjustment may be made while the machine is running if it is desired to change the width of the feather at different parts of the sole margin. By lifting the handle 140 the lower latch lever 132 may be swung below the plane of the segmental slide 152, thus leaving the slide 66 free to be moved forwardly to permit the convenient removal and replacement of the chamfer knife slide, as will hereinafter be explained.

The chamfer knife 26 is provided for the purpose of chamfering or beveling the sole edge adjacent to the lower or unchanneled face of the sole for a purpose well known in the art. The chamfer knife is located at the side of the edge gage which is foremost in the line of feed of the work. The shank portion of the chamfer knife, as best shown in Figs. 2, 8, 10, 14 and 15, is fitted within a notch 168 in a supporting slide 170 and is rigidly secured to the slide by means of a screw 172. The cutting edge of the chamfer knife projects upwardly above the upper surface of the work table at an angle of approximately forty-five degrees. A rib 174 on the shank of the chamfer knife is received in a corresponding horizontal groove in the chamfer knife slide 170 and assists in accurately locating the knife relatively to the slide and in preventing displacement of the knife.

While a sole is being fed through the machine by means of feed mechanism hereinafter to be described, the sole is swung about the edge gage 24 so that the proper relationship will be retained between the sole edge and the channeling knives as the points of operation of the knives are transferred around the sole. The chamfer knife is located at one side of the edge gage and accordingly it is obvious that as the sole is swung about the edge gage, the portion of

the sole edge which is opposite the chamfer knife will be moved more or less relatively to the edge gage in a direction transverse to the direction of feed. To assure that the chamfer knife shall continuously be maintained in predetermined operative relation to the sole edge as the sole is swung about the edge gage, the slide 170, which carries the chamfer knife at its forward end, is movable horizontally at right angles to the direction of feed and is yieldingly pressed toward the sole edge. The chamfer knife slide 170 is further provided with a follower or knife gage 176 which extends transversely across the cutting edge of the chamfer knife within the plane occupied by the sole, when the latter is upon the work table.

The follower or chamfer knife gage 176 is formed with a depending shank portion 178 which is secured to the chamfer knife slide 170. While a sole is being operated upon, the follower or gage 176 is continuously held against the sole edge by means of yielding pressure against the slide 170 and thus said gage functions to determine the location of the chamfer knife relatively to the sole edge. The gage 176 is so located relatively to the chamfer knife, in the direction of movement of the slide 170, that the knife is continuously maintained in proper cutting relation to the sole edge irrespective of the turning movements of the sole about the edge gage. The wall 64 which encloses the work table is provided at the rear of the work table with a notch 180 (Figs. 8 and 14) into which the chamfer knife and the knife gage or follower 176 project, the notch permitting the knife and knife gage to be normally located somewhat nearer the front of the machine than the edge gage, to insure that said knife and knife gage will be engaged by the work as the latter is properly positioned relatively to the channel knives and edge gage.

The chamfer knife slide 170 is mounted in a horizontally disposed dove-tailed guideway 182 formed in a bracket 184 that is rigidly secured to the stationary work-table support 68. The slide 170 is provided with ribs 186 (Fig. 10) which extend horizontally along the upper and lower edges of the slide. The ribs 186 are received in the undercut or grooved portions of the dove-tailed guideway 182. The ribs are notched or cut away at 188 and the undercut portions of the guideway are notched at 190 (see Fig. 10) to facilitate the removal of the slide from the guideway, as will hereinafter be explained. At its rear extremity, the chamfer knife slide is provided with a projecting stop lug 192 (Figs. 2 and 14) which extends beyond the bracket 184 and is adapted to co-operate with the rear extremity of the latter to limit the forward movement of the chamfer knife slide 170. The

slide 170 is yieldingly pressed toward the feed table 22 by means of a spring 194 which is secured at one end to the lug 192 and at the opposite end to the pin 196 on the bracket 184.

- The follower or knife gage 176 is offset laterally from its depending shank portion 178 and the forward portion of the gage is rounded, as indicated at 198, to provide a smooth surface to meet the oncoming work. The offset portion of the follower 176 is undercut at an angle suitable to receive the blade of the chamfer knife. The follower or gage 176 is carried by a block 200 (Figs. 8 and 15) which is removably secured to the slide 170 by means of a screw 202. A rib 204 on the block 200 engages a corresponding groove in the slide 170 to prevent the block from turning about the screw 202.
- In order that the cutting edge of the chamfer knife may be readily exposed for sharpening without the necessity of removing the knife from the slide 170, the shank of the chamfer knife follower 176 is hinged at 206 to the block 200 and is normally maintained in vertical or operative position by means of a finger 208 pivoted at 210 to the shank of the follower and arranged to overlie the block 200 so as to prevent the follower from being swung away from the chamfer knife.
- To facilitate sharpening of the chamfer knife, the slide upon which it is mounted is adapted to be removed from its guideway in the bracket 184. To this end, the stop lug 192 is pivotally connected to the slide 170 in the following manner:—A laterally offset ear 212 (Fig. 14) is received in a notch 214 at the rear of the slide 170 and is pivoted on a vertical pintle 216 carried by the slide. The tension of the spring 194 will hold the stop lug 192 in the position shown in Fig. 14 so that the lug will perform its function of limiting the forward movement of the slide. By detaching the spring 194 from the stop lug 192, the latter may be swung bodily backward about the pintle 216 until it is clear of the bracket 184. Before the slide 170 can be withdrawn from the guideway 182, it is necessary that the work table 22 shall be disconnected from the bell-crank lever 98. This is accomplished by manipulating the latch 122 and swinging the handle 110 to its rearmost position, thereby disengaging the roll 114 from the cam slot 112 in the bell-crank lever. This permits the chamfer knife slide 170 to be moved forwardly until the greater portion of the slide is clear of the guideway 182 and the portions of the ribs 186 which are at the rear of the notches 188 are brought into registry with the notches 190 in the undercut portion of the guideway 182. The slide 170 may then be easily removed from the guideway 182 by a lateral movement of the slide.
- A treadle connection may be provided for

withdrawing the chamfer knife from the path of the work, either for the purpose of facilitating the introduction of the work into the machine, or to prevent the chamfer knife from operating upon the work. For this purpose, the free extremity of the stop lug 192 is extended beyond the bracket 184 and an arm 218 (Figs. 2, 8 and 10) is pivoted at 220 to the bracket 184 for vertical swinging movement in the plane of the projecting end of the stop lug 192. At its upper end the arm 218 is connected by means of a link 222 to one arm of a bell-crank lever 224 which is pivoted at 226 to the frame of the machine. The other arm of the bell-crank lever 224 may be connected, by means of a rod 227, with a suitable foot treadle (not shown). A spring 288, one end of which is secured to the arm 218 and the other end to a pin projecting from the bracket 184, normally holds the arm 218 against a stop 229 on the bracket 184.

The channeling knife 28 and the edge-slitting knife 30 are rigidly but adjustably secured to knife carriers 230 and 232, respectively, by means hereinafter to be described in detail. The two knife carriers 230 and 232 consist of elongated bars which are rectangular in cross-section and are made hollow, as shown clearly in Fig. 11, to reduce their weight. The knife carriers 230 and 232 are arranged side by side in sliding contact and are mounted for movement toward and from the work table in a vertical guideway 234 formed in one face of the horizontally movable knife carrier slide 38. The opposite ends of the knife slide 38 are notched as indicated at 236 to receive supporting blocks 238 (Fig. 6) which are rigidly secured to the frame 20 and have parallel bearing faces for engaging the upper and lower sides of the notches 236 and thus guiding the slide 38 for horizontal reciprocation.

The knife carrier 230 is mounted for vertical movement in the guideway 234 in face-to-face sliding contact with the knife carrier 232. A screw 240, which is threaded in the upper end of the carrier 230, extends freely through an aperture in a stop plate 242 carried by the knife carrier slide 38 and the head of the screw 240 overlies the stop plate 242 to limit the downward movement of the knife carrier and the parts carried thereby. The knife carrier 230 is allowed a yielding upward movement in the guideway 234 by means of a "grasshopper" spring 244 which is coiled around a stud 246 carried by an extension 248 of the stop plate 242, one leg of the spring bearing downwardly against the head of the screw 240 and the other leg of the spring bearing against the head of a screw 250 in the stop plate extension 248. The head of the screw 250 is radially notched to receive the adjacent leg of the spring 244 which serves to lock the screw in adjusted

position. As shown, the head of the screw 240 is also radially notched to receive the other leg of the spring 244, thus holding the latter in fixed relation to the screw and also locking the screw against turning. By lifting the spring from the notched head of the screw 240, said screw may be turned to adjust the channeling knife vertically with respect to the work table. By releasing the spring 244 from the screw 250, the latter screw may be turned to vary the tension of the spring 244.

The knife carrier 232 is substantially similar in construction to the knife carrier 230, just described, and it is mounted in the guideway 234 and is spring-pressed downwardly in the same manner as the slide 230, by means of a spring and associated parts designated by reference numerals similar to those applied to corresponding parts associated with the carrier 230.

In order to provide for accuracy and uniformity in the channeling operations upon different soles, it is desirable to provide means for insuring against play or lateral displacement of the knife carriers in the guideway 234. To this end, the knife carriers 230 and 232 are provided with vertical tongues 252 and 254, respectively, (Figs. 10 and 11). Each of the tongues 252 and 254 is cut away intermediate its ends, as indicated at 256 in Fig. 10, to receive the free extremity of a lifting lever 258 which is pivoted at 260 to the frame 20. At the end remote from the knife slides the lever 258 is connected, by means hereinafter to be explained, with a foot treadle, not shown. The tongues 252 and 254 are received in a vertical groove 264 in the knife carrier slide 38 and the tongues 252 and 254 and the groove 264 are carefully machined so that the tongues have close sliding fit in the groove. This interengagement of the tongues and the groove reinforces the knife carriers against the thrust of the channeling knives and prevents lateral displacement of the knife carriers such as might be permitted by reason of play resulting from wear between the knife carrier 230 and the adjacent slide 42 which carries the feed dog. By reason of the interfitting of the tongues 252 and 254 in the groove 264, the knife carriers 230 and 232 can be maintained in parallel vertical relation at all times so that the relative positions of the channeling knife and the edge-slitting knife are invariable and uniformity of operation upon different soles is insured.

The channeling knife 28, which is attached to the carrier 232, is formed with a horizontal cutting edge 268 (Figs. 3, 7, 8 and 13) and a vertical cutting edge 270 which co-operate to cut a channel in the work, as indicated at 272 in Fig. 3, thereby forming an inner lip 274. The cutting edges

268 and 270 are formed on a shank 276 (Fig. 13) which is disposed at an angle to the knife carrier 230. To support the channeling knife 28, the knife carrier 230 has a laterally extending foot 278 (Figs. 8 and 10) to which a knife block 280 is secured. The knife block 280 is secured to the foot 278 by means of a bolt 282 and nut 284, the bolt 282 extending through a horizontal slot 286 in said foot. The slot 286 permits adjustment of the knife block 280 horizontally relatively to the knife carrier 230. To maintain the knife block 280 in fixed relation to the carrier 230, a rib 288 on the knife block interlocks with the slot 286 in the carrier 80 foot 278. The bolt 282 is provided with a head 290 which is grooved to receive horizontal ribs 292 on the foot 278 of the knife carrier 230 so that the bolt head 290 is prevented from turning. An adjusting screw 85 294 is threaded horizontally through the bolt head 290 and is arranged with its inner end bearing against the face of the knife carrier 230. The screw 294 may be turned to adjust the bolt 282 outwardly in the slot 286 for the purpose of adjusting the knife block 280 relatively to the foot of the knife carrier, and thereby adjusting the channeling knife 28 away from the edge-slitting knife 30. The shank of the channeling knife 28 is received in a groove 296 in the knife block 280 and is held therein by means of a cap plate 298 which is clamped against the knife shank by means of bolts 300. An abutment screw 302 is threaded through a portion of the knife block 280 at an angle to the shank of the channeling knife, as shown in Figs. 7, 10 and 13, and it is provided with a conical inner end for engaging the upper extremity of the knife shank in such a way that the screw 302 may be turned to adjust the position of the knife shank in the groove 296 and thereby to vary the elevation of the edge of the channeling knife relatively to the associated presser foot 34.

The edge slitting knife 30, which is attached to the knife carrier 232, is formed with a horizontal cutting edge 306 (Fig. 12) to cut a slit 308 (Fig. 3) inwardly from the sole edge so as to form an outer lip 310 and a feather 312. In certain classes of work it is desirable to increase the width of the feather along certain portions of the sole margin, especially at the shank of the sole. It is desirable, however, to prevent increasing correspondingly the width of the outer lip at such portions of the sole and thus to insure that when the lip has been turned up, it will not be higher than along the remaining portions of its length. Accordingly, there may be associated with the edge-slitting knife 30, a lip trimming knife such as shown at 32, the knife 32 having a vertical cutting edge for trimming off the surplus portion of the outer lip where the lip is of

maximum width. The action of the lip knife 32 is illustrated in Fig. 3, wherein the surplus portion of the outer lip which has been trimmed by the knife is shown at 314. The lower edge of the lip trimming knife 32 is inclined to conform to the transverse bevel of the edge-slitting knife, thus enabling the vertical cutting edge of the lip trimming knife to abut the horizontal cutting edge of the slitting knife.

The edge-slitting knife 30 and the lip trimming knife 32 are both supported upon a knife block 316 which in turn is secured to a laterally extending foot 318 at the lower end of the knife carrier 232. A bolt 320 and nut 322 secure the knife block 316 to the foot of the knife carrier 232, the bolt 320 extending through a horizontal slot 324 in the carrier foot to permit horizontal adjustment of the knife block relatively to the knife carrier. A rib 326 on the knife block 316 interlocks with the slot 324 to maintain the knife block in fixed relation to the carrier. Horizontal ribs 328 on the foot of the knife carrier 232 are received in a groove in the head of the bolt 320 to prevent the bolt head from turning, and an adjusting screw 330, which is threaded through the bolt head, bears at its inner end against the knife carrier 232 so that by turning said screw the knife block 316 may be adjusted to move the edge-slitting knife and the lip trimming knife away from the channeling knife 28.

The edge-slitting knife is provided with a shank portion 332 which is clamped between the lower portion of the knife block 316 and a clamp plate 334 (Figs. 7 and 12) by means of bolts 336 which extend through the knife block and are threaded into said clamp plate. The opposite longitudinal edges of the knife shank 332 are beveled and are received in grooves in the knife block 316 and clamp plate 334. A screw 338, which is threaded through the clamp plate 334, bears at its inner end against the knife block 316 and serves to increase the clamping action of the plate and to lock the clamping screws 336. An abutment screw 340, which is threaded through an ear 342 (Fig. 7) on the block 316, provides means whereby the knife 30 may be adjusted when the screws 336 and 338 have been loosened.

The lip trimming knife 32 is provided with a shank of reduced width which is clamped between the knife block 316 and a clamping plate 344. The opposite longitudinal edges of the shank of the lip knife are beveled and are received in dove-tailed grooves in the knife block and in the clamping plate 344. The clamping plate 344 extends rearwardly from the knife 32 and at its rear extremity is provided with a rib 346 which bears against the block 316. A clamping screw 348 extends through an

aperture in the block 316 and is threaded within the clamping plate 344 at a point between the rib 346 and the knife 32 and serves to bind the clamping plate against the shank of the knife. To remove or adjust the knife 32 it is necessary only to loosen the clamping screw 348. By independently mounting the edge-slitting knife 30 and the lip trimming knife 32, as above described, these knives may be separately removed for the purpose of grinding and they may be adjusted relatively to each other to take up for wear.

The presser feet 34 and 36 are associated with the knives 28 and 30 respectively, and each presser foot is arranged to rest upon the surface of the work in proximity to the associated knife to hold the work down upon the work table as the knife is cutting and to limit the depth of the cut made by the knife. In addition, and in accordance with an important feature of the present invention, the presser feet function during the forward or idle strokes of the channeling knives to impart auxiliary feed movements to the work whereby the work is caused to advance with the knives so that the knives will be enabled to cut the work immediately at the beginning of each backward stroke. As shown, each presser foot consists of a rectangular bar which is vertically disposed and is formed with a rounded lower edge at the side remote from the knives, thus enabling the foot to slide freely over the work during the backward or cutting strokes of the knives.

As best shown in Figs. 8, 9 and 12, the upper portion of the presser foot 36 is received in a socket in the knife block 316 and is secured in the socket by means of a screw 350 which extends loosely through a vertical slot 352 in the block 316 and is threaded into the shank of the presser foot. The head of the screw 350 bears against the outside of the block 316 so that when the screw is tightened, the presser foot is securely clamped in place. The slot 352 permits the presser foot to be raised or lowered to adjust it relatively to the cutting edge of the knife 30. A minute adjustment of the foot 36 may be obtained by means of an adjusting screw 354 which is threaded through the knife block 316, the inner end of said screw having a conical tip which bears against the side of an aperture 356 in the shank of the presser foot. The upper or shank portion of the other presser foot 34 is received in a socket in the knife block 280 and is adjustably secured therein by means which is substantially identical with the means just described for securing the presser foot 36 to the knife block 316.

As the presser feet are moved with the channeling knives during the backward or cutting strokes of the latter, they function in

- the well-known manner to gage the distance to which the knives penetrate the work and thus to determine the depth of the cuts made thereby. During the forward or non-cutting strokes of the knives and concurrent idle backward movements of the feed dog, the presser feet function to feed the work along with the knives as above described. To enable the presser feet to perform this feeding function, the bottom faces of the feet are shaped, as best shown in Fig. 12, to provide a sharp edge or corner at the forward side of each presser foot, this edge being adapted to bite into the work to a certain extent as the presser foot moves in the direction of feed. The shape of the bottom of the presser foot is such, however, that while its forward edge bites into the work sufficiently to feed the work positively, the surface work is not roughened or injured thereby. The presser foot 36 is arranged with the forward or work engaging edge of its bottom face substantially in or slightly to the rear of the vertical plane of the cutting edge of the knife 30.
- As the knife 30 is moved backwardly to cut the sole and form a lip thereon, the portion of the sole stock which overlies the knife is displaced slightly above the upper face of the sole by the thickness of the knife. With the above-described relative arrangement of the presser foot 36 and knife 30, the portion of the sole stock which is upwardly displaced by said knife is located directly ahead of the presser foot. By reason of this upward displacement of the sole stock by the knife 30, it will readily be appreciated that the presser foot 36 will be enabled, upon its forward stroke, to bite into the sole in such a manner as to insure a positive feed of the sole by the presser foot. It will be seen, therefore, that the presser foot 36 and the knife 30 actually co-operate to effect the feed of the work. It is to be understood, however, that such co-operation of the presser foot and the knife is not regarded as an essential feature of the invention inasmuch as it has been found to be practicable to feed the work in a reliable manner by means of the presser foot alone. It has also been found that a satisfactory and positive feed of the work may be obtained without arranging both presser feet directly behind the respective channeling knives, and it will be observed that the presser foot 34 has not been arranged directly behind the channeling knife 28 although it may be so arranged without departing from the spirit of the invention.
- In order that the channeling knives and the presser feet may be reciprocated horizontally in unison to cut and feed the work, the slide 38, in which the knife carriers 230 and 232 are mounted, is reciprocated by actuating mechanism deriving its motion from

the eccentric 46 on the main shaft 44. To this end, the slide 38 is connected by a link 360 with the depending arm 362 of a lever which is also provided with a shorter upwardly extending arm 364. As best shown in Figs. 4 and 5, this two-armed lever is provided with a duplex hub 366 which is mounted to rock upon a fixed shaft 370 that is supported in ears 372 extending from the frame 20. The lever arm 364 extends upwardly from the hub 366 and is pivoted to an eccentric rod 374 having an eccentric strap 376 which encircles the eccentric 46. It is desirable that means be provided for varying the rate of feed of the work while the machine is in operation and especially for slowing down the work feed while the relatively short curve at the toe of the sole is being cut. To this end, the depending lever arm 362 is provided with an elongated arcuate slot 378 in which a block 380 is adapted for sliding adjustment, the link 360 being bifurcated to straddle the lever arm 362, and the block 380 carrying a stud 382 which is journaled in the bifurcated end of the link. The link 360 may be swung upwardly about its pivotal connection with the slide 38 to shift the block 380 in the slot 378 so as to move the block toward or from the axis of oscillation of the two-armed lever and thus to vary the extent of reciprocation of the slide 38 and consequently of the knives and the presser feet. To this end the link 360 is connected to one end of a curved arm 384 (Fig. 1) the opposite end of which is mounted to rock upon a fixed stud 386. The connection between the link 360 and the arm 384 comprises a pin 388, one end of which is fast in the curved arm 384 and the opposite end of which is received in a longitudinally elongated slot 390 in the link 360. The pin 388 is connected by means of a short link 392 with an arm 394 that is fixed upon the forward end of a horizontal rock-shaft 396. The rock-shaft 396 is arranged parallel to the main shaft 44 and is mounted to turn in bearings 398 (Fig. 4) on the frame 20. At its rear extremity the rock-shaft 396 is provided with an arm 400 which may be connected by a chain 402 with a foot-treadle (not shown). A spring 404, which is coiled about the rock-shaft 396, tends to rotate said shaft in a direction to hold the treadle in elevated position and to maintain the block 380 at the lower end of the slot in the lever arm 362, so that, under normal operating conditions, a stroke of maximum length will be imparted to the knife slide 38. Upon depression of the treadle connected with the arm 400, the block 380 may be moved upwardly in the slot 378 to shorten the length of stroke of the knife carrier slide 38, and upon the release of said treadle the block 380 will be immediately returned by the action of the spring 404 to the lower end of

the slot 378, thus automatically restoring the slide-actuating mechanism into condition to reciprocate the slide 38 through strokes of normal maximum length.

- 5 To enable the work to be introduced between the presser feet and the work table in position to be operated upon, means is provided for lifting the knives and presser feet bodily with relation to the work table.
- 10 This means comprises the lever 258 hereinbefore mentioned, and in order that this lever may be conveniently actuated by the operator, its rear extremity may be connected with the bell-crank lever 224 by means of a link 406 such as shown in Fig. 2. By means of this arrangement the lever 258 will be actuated in unison with the bell-crank lever 224 upon depression of the treadle connected with the last-named lever,
- 15 and as a result both channeling knives will be lifted and the chamfer knife will be withdrawn simultaneously from their operative positions. If desired, the lever 258 may be connected with a foot treadle independently of the chamfer knife. As best shown in Fig. 10, the forward end of the lifting lever 258 extends through a slot 408 in the frame 20 and through a slot 410 in the rear of the knife carrier slide 38 and said lever projects
- 20 into the notch 256 which is formed between the upper and lower sections of the tongues 252 and 254 on the knife carriers 230 and 232. The notch 256 is wider than the co-operating end of the lever 258, thus permitting the knife carriers 230 and 232 to move vertically to accommodate themselves to different thicknesses of work without being interfered with by said lever. The depth of the notch 256 is also greater than the thickness of the lever 258, as shown clearly
- 25 in Fig. 11, thus permitting the knife carrier slide 38 to reciprocate horizontally relatively to said lever. It will be desirable to lift the knives and the presser feet in the manner above described if the channeling operation is to begin at any point intermediate the ends of the sole as, for example, at the rear of the shank portion. The channeling knives and the presser feet may be lifted in
- 30 a similar manner for the purpose of withdrawing the knives from the sole when the cutting has progressed to a corresponding portion of the sole margin at the opposite side of the sole from the point of beginning.
- 35 The feed dog 40, as best shown in Figs. 6, 8 and 10, is bifurcated at its lower extremity to provide two feed points or teeth 412 which are inclined forwardly in the direction of feed. One tooth 412 is offset laterally from the other and the teeth may be so arranged relatively to the edge gage that they will dig into the sole at opposite sides of the between-substance and thereby avoid injuring or weakening the latter. The teeth
- 40 of the feed dog are formed at the lower end

of an inclined shank and the latter is secured by means of a screw 414 to a carrier which is indicated by the general reference numeral 416 and is movable in a vertical guideway 418 in the horizontally reciprocating slide 42. 70

The feed dog 40 is so mounted and actuated that when no work is present in the machine the feed dog moves through an orbital path of substantially elliptical shape the longest diameter of which extends substantially horizontally or in the direction of work feed. To produce this movement of the feed dog, the feed dog carrier 416 is reciprocated vertically by the eccentric 50 while the carrier slide 42 is reciprocated 80 horizontally by the eccentric 48. Thus the component of the orbital movement of the feed dog in the direction of work feed is derived from the horizontally reciprocating slide 42 while the component of movement of the feed dog in a direction at right angles to the direction of work feed is derived from the vertically reciprocating carrier 416. As shown, the carrier slide 42 is located in front of the knife carrier slide 38 and is reciprocated horizontally in sliding engagement with the slide 38. The opposite ends of the slide 42 are provided with notches corresponding to the notches 236 in the slide 38, and the bearing blocks 238 extend 90 through the notches in the feed dog carrier slide to support the latter. At their front sides the blocks 238 are provided with upwardly and downwardly projecting flanges 239 which overlie the front side of the slide 42 to prevent forward displacement of the slides 38 and 42. Rearward displacement of the slides 38 and 42 is prevented by the portions of the head 20 to which the blocks 238 are secured. 105

The feed dog carrier 416 is made in two sections 420 and 422 which are positioned end to end in the guideway 418 and are longitudinally recessed to receive between them a coiled spring 424 which tends to hold them apart. To support the lower section 422 of the feed dog carrier, a bolt 426 is provided, the lower portion of which is threaded into the lower carrier section 422. The bolt 426 extends upwardly within the convolutions of the spring 424 and through an aperture in the top of the upper carrier section 420. At its upper extremity the bolt 426 is provided with a head 428 which normally engages the top of the upper carrier section 420 to limit the expansion of the spring 424 and to provide means whereby the upward movement of the upper carrier section 420 may be communicated to the lower carrier section 422. The bolt 426 may be turned, by means of its head 428, to vary the upper limit of movement of the feed dog and normal extent of separation of the upper and lower sections of the feed dog carrier. This adjustment is effective to vary the vertical 115

relation between the path of movement of the feed dog and the plane of the work table for a purpose hereinafter explained. A set screw 430 in the lower carrier section 422 engages an unthreaded extension 432 of the bolt 426 and locks the bolt in adjusted position. The upper section 420 of the feed dog carrier is supported by means of an eccentric rod 434 which is pivoted to the section 420 at 435 (see Fig. 6). At its upper extremity the eccentric rod 434 carries an eccentric strap 436 which encircles the eccentric 50 at the front end of the main shaft 44. A disk or cap 438, which is secured to the eccentric 50 by a screw 440, prevents forward displacement of the eccentric strap, while rearward displacement of said strap is prevented by the front bearing 58 in which the main shaft is journaled. By means 20 of the above described two-part construction of the feed dog carrier, the feed dog is adapted yieldingly to engage the work and is enabled to be actuated through an orbital path for feeding the work as previously 25 stated.

To prevent lateral displacement of the sections of the feed dog carrier, such as might be permitted by reason of play resulting from the wear between the adjacent 30 knife carrier slide 38 and the feed dog carrier slide 42, and to insure that the feed dog carrier sections will be accurately guided in their vertical movements, each of said sections is provided with a tongue 442 (see Fig. 35 11), which is closely interfitted within a vertical groove 444 in the slide 42. These tongues 442 increase the extent of bearing surface between the feed dog carrier sections and the adjacent guiding walls of the slide 40 42 and help to eliminate undue frictional 45 contact of said carrier sections with the slide 42.

In order to limit the downward movement of the feed dog 40, under the pressure 45 of the spring 424, so as to predetermine the extent to which the feed dog is permitted to penetrate the work, and to prevent the feed dog from engaging the work table when no work is present beneath the feed dog, an adjustable stop member 446 is provided (Figs. 6 and 8) having a horizontal lower portion 448 and a vertical arm 450. The vertical arm 450 is rigidly secured to a slide 452 (Fig. 11) which is freely movable vertically 50 in a dove-tailed guideway in the feed dog carrier slide 42 so as to permit vertical adjustment of the stop member 446 and also to enable said stop member to be actuated to lift the feed dog or to prevent the feed dog 55 from engaging the work, as will hereinafter be explained. The horizontal lower portion 448 of the stop member 446 has a rearwardly projecting lug 454 (Fig. 8) which extends through an aperture 456 in the slide 42 and is received in a recess 458 in the lower sec- 60 tion 422 of the feed dog carrier. The lug 454 on the stop member has an inclined upper face adapted to engage a correspondingly inclined face or shoulder 460 at the upper end of the recess 458. Normally the 65 stop member 446 is supported by means of an abutment screw 462 (Figs. 6 and 8) which is threaded vertically through the horizontal portion 448 thereof, the lower end of said screw projecting below the portion 448 of 70 the stop member and bearing against a fixed abutment 464 (Fig. 8) on the feed dog carrier slide 42. The screw 462 may be turned to adjust the stop member 446 upwardly or downwardly to vary correspondingly the 75 limit to which the feed dog is permitted to descend. A lock nut 466 on the screw 462 bears against the adjacent portion of the stop member 446 to prevent accidental turning of the screw. By turning the screw 462, 80 the limit of downward movement of the feed dog under the influence of the spring 424 may be varied in accordance with the thickness, density or other characteristic of the work and the extent to which it is desired to 85 have the teeth of the feed dog penetrate into the work. The range of vertical movement of the feed dog will be determined by the relative adjustment of the bolt 426 and the screw 462, and the upper and lower 90 limits of movement of the feed dog may be adjusted in accordance with the character of the work. The stop member 446 serves to relieve the work from excessive pressure of the feed dog tending to create undue friction 95 between the work and the work table. As shown, the eccentric 48, which moves the feed dog horizontally, is designed to have a somewhat greater throw than the eccentric 46 which actuates the knives and the presser feet and consequently, under the usual conditions of adjustment of the connections between the eccentric 48 and the feed dog slide 100 42, the work will be advanced through a somewhat longer feed movement by the feed dog than by the presser feet. By turning the bolt 426, the vertical diameter of the orbital path of the feed dog may be shortened or lengthened and consequently the horizontal diameter of the path will be 105 moved respectively toward or from the work. By modifying the path of the feed dog in this manner the feed dog may be rendered capable of engaging the work at different 110 points in the line of feed and of leaving the work at different points in the line of feed so that more or less of the forward movement of the feed dog may be made effective to advance the work. In practice adjustment of the bolt 426 is made in accordance with the 115 thickness of the work to insure that the horizontal diameter of the path of the feed dog shall be located substantially in the plane of the upper surface of the work or, in other words, to insure that substantially the entire 120 125 130

- amount of forward movement of the feed dog will be effective to feed the work, whatever the thickness of the work may be. The described construction, however, also affords 5 a means for varying the length of the feed movements imparted to the work by the feed dog relatively to the length of feed strokes imparted to the work by the presser feet.
- 10 The horizontal reciprocating movement of the feed dog is derived from the feed dog carrier slide 42. The slide 42 is reciprocated horizontally by means of mechanism similar to that which reciprocates the knife carrier 15 slide 38. This mechanism comprises a two-armed lever 468 (Figs. 4 and 5) which is similar to the lever already described for actuating the knife carrier slide 38. The lever 468 has a duplex hub which is mounted 20 to rock upon the shaft 370 and is further provided with a depending arm 474 (Figs. 1 and 6) and a shorter upwardly extending arm 476, the depending arm 474 being connected with the hub of the lever by means 25 of a web portion 478 which is offset from said hub to avoid the depending arm of the lever which operates the knife carrier slide. The lever arm 474 is connected by means of a link 480 with the feed dog carrier slide 42, 30 while the upwardly extending arm 476 is pivoted at 482 to an eccentric rod 484 carrying an eccentric strap 486 which encircles the eccentric 48.
- 35 In addition to the above described horizontal movement of the feed dog, which is derived from the slide 42, the feed dog is reciprocated vertically by the eccentric 50, through its operative connections with the feed dog carrier section 420, so that the desired four-way motion of the feed dog is obtained. The relative radial arrangement 40 of the eccentrics 48 and 50 is such that the feed dog is lowered into engagement with the work at the beginning of each forward 45 or feed stroke and is raised to release the work during the latter part of each forward stroke. The strength of the spring 424 is such that during the downward movement of the upper section 420 of the feed dog carrier, said spring will not yield, and consequently both the upper and lower carrier sections 420 and 422 will be lowered in unison, the spring 424 at this time acting the same as a rigid connection between the carrier sections. After the feed dog has engaged the work, the upper carrier section 420 moves downwardly away from the head of 55 the bolt 426, compressing the spring 424 so that the teeth of the feed dog penetrate the work and a firm feeding hold is secured thereon. The feed stroke of the feed dog is then effected by means of the forward movement of the slide 42. At the termination of 60 said feed stroke, the compression of the spring 424 is relieved as the upper section

420 of the feed dog carrier rises. Thereafter, when said upper carrier section 420 again engages the head 428 of the bolt 426, continued upward movement of said carrier section is positively transmitted to the lower 70 carrier section 422 through the bolt 426 and as a result the feed dog is positively lifted from the work. The feed dog is then moved idly backward by the action of the slide 42.

75 It is desirable that the length of the horizontal stroke of the feed dog 40 shall be varied concurrently with and proportionally to the variation of the length of stroke of the knives and presser feet when cutting around the toe or other more or less abruptly curved portions of the sole margin. Accordingly, the link 480 is connected with the depending lever arm 474 in the same manner as the link 360 is connected with the respective lever arm 362. As shown, the lever arm 474 is provided with an arcuate slot 488 in which is slidably received a block 490. The block 490 carries a pin 492 which is journaled in the bifurcated rear extremity of the link 480. The link 480 is provided with a longitudinal slot 494 through which extends the pin 388 which is carried by the curved arm 384. The slots 378 and 488 in the arms 362 and 474 are formed upon an arc of a circle which has the pivotal connections of said links with the respective slides 38 and 42 as a center, when said lever arms are positioned in radial alinement or, in other words, when the slides 38 and 42 are at the ends of the cutting and main feeding strokes. Inasmuch as the angular movement of the lever arms 362 and 474 is slight, it is obvious that with the above described arrangement of the slots in said arms, a minimum amount of resistance is offered to the shifting of the blocks 380 and 490 in said slots. The slots in the lever arms 362 and 474 are of such length that the blocks mounted therein may be positioned with the pins 382 and 492 in axial alinement with the shaft 370, in which case no throw will be imparted by the lever arms to the respective slides or, in other words, the throw of the lever arms will be nullified, and consequently the work will not be fed and no movement will 100 be imparted to the knives. The eccentrics 46 and 48, being disposed diametrically opposite each other as shown, the two slides 38 and 42 and the parts carried thereby are reciprocated simultaneously in opposite directions through the connections above described.

105 As hereinbefore indicated, the shortening of the feed stroke of the feed dog, and the shortening of the feed strokes of the knives and presser feet, facilitates the swinging of the sole, particularly at the toe thereof. Further to facilitate the swinging of the sole while the toe is being operated upon, it is desirable that the feed dog should be pre- 110

vented from performing at this time a rapid succession of downward movements each of which would cause it to engage the work under pressure and thus interfere with the 5 swinging or turning of the work. Accordingly provision is made whereby, when the feed strokes of the feed dog and presser feet have been shortened to a predetermined extent, the eccentric 50 will be rendered in- 10 effective to depress the feed dog into engagement with the work. To this end, as best shown in Figs. 1, 8 and 11, the curved arm 384 is arranged to extend beneath an overhanging portion 496 of the stop mem- 15 ber 446, and said curved arm carries an adjustable abutment screw 498 for engaging said overhanging portion of the stop mem- 20 ber. With this arrangement of parts, as the links 360 and 480 have been swung up- 25 wardly to shorten the feed strokes of the feed dog and the presser feet, the curved arm 384 is also swung upwardly about its pivot 386, and after a certain amount of lost motion has occurred between said arm and the stop 30 member 446, the abutment screw 498 engages the stop member. Continued upward movement of the arm 384 lifts the stop member 446 and the lug 454 carried thereby obstructs the downward movement of the lower feed 35 dog carrier section 422, thus preventing the feed dog from being depressed into engagement with the work and enabling the work to be freely turned or manipulated by the operator. If the links 360 and 480 are 40 swung upwardly a sufficient amount to nullify the throw of the lever arms 362 and 474, there will be substantially no downward movement of the feed dog. It will be understood that while the feed dog is thus 45 held from effective feeding engagement with the work, the successive downward movements imparted to the upper feed dog carrier section 420 by the eccentric 48 will be taken up by the compression of the spring

The present embodiment of the invention has been described with considerable particularity in order to make clear to those skilled in the art the precise details of construction which may be employed in its use. It is to be understood, however, that the invention is not limited to the details of construction herein shown except in so far as set forth in the following claims.

Having thus described my invention, what I claim as new and desire to secure by Letters Patent of the United States is:—

1. In a machine of the class described, feeding means intermittently operative to feed the work, cutting means movable opposite to the direction of feed to cut the work while said feeding means is operative and movable to starting position while said feeding means is inoperative, and means con- 60 stantly in engagement with the work for im-

parting an additional feed movement to the work during the movement of the cutting means to starting position.

2. In a machine of the class described, feeding means intermittently operative to feed the work, cutting means movable opposite to the direction of feed to cut the work while said feeding means is operative and movable to starting position while said feeding means is inoperative, and means for 70 gaging the relation of the cutting means to the work, said gaging means being constructed and arranged to impart an additional feed movement to the work during the movement of the cutting means to starting 75 position.

3. In a machine of the class described, cutting means, work feeding means, means for moving the cutting means opposite to the direction of feed to cut the work while the work is being fed, means for operating the feeding means to feed the work while the cutting means is operating to cut the work, and a member movable with the cutting 85 means for gaging the relation of the cutting means to the work and for imparting an additional feed movement to the work while the cutting means is ineffective to cut the work.

4. In a machine of the class described, feed mechanism intermittently effective to advance the work, a reciprocating knife moving opposite to the direction of feed to cut the work while the work is being advanced by said feed mechanism, and a member effective during the cutting stroke of the knife for gaging the depth of the cut in the work and during the noncutting stroke of the knife for advancing the work with the knife.

5. In a machine of the class described, feeding means intermittently operative to feed the work, cutting means movable opposite to the direction of feed to cut the work while said feeding means is operative and movable to starting position while said feeding means is inoperative, and a presser foot for advancing the work with the cutting means while said feeding means is inoperative.

6. In a machine of the class described, feeding means intermittently operative to feed the work, cutting means movable opposite to the direction of feed to cut the work while said feeding means is operative and movable to starting position while said feeding means is inoperative, and a reciprocating presser foot movable forwardly to advance the work while said feeding means is inoperative and movable backwardly relatively to the work while said feeding means is feeding the work.

7. In a machine of the class described, feeding means intermittently operative to feed the work, cutting means movable op-

- posite to the direction of feed to cut the work while said feeding means is operative and movable to starting position while said feeding means is inoperative, and a presser 5 foot operative while the cutting means is cutting the work to gage the depth of the cut and while the cutting means is moving in the direction of feed to advance the work with the cutting means.
- 10 8. In a machine of the class described, feeding means intermittently operative to feed the work, cutting means movable opposite to the direction of feed to cut the work while said feeding means is operative 15 and movable to starting position while said feeding means is inoperative, and a presser member movable in unison with the knife to gage the depth to which the knife penetrates the work and cooperating with said 20 knife to advance the work with the knife during the non-cutting stroke of the knife.
9. In a machine of the class described, a knife reciprocating in the line of feed of the work and arranged to cut upon its backward 25 stroke, means for advancing the work during the backward stroke of the knife, and a presser member for determining the depth of the cut and for feeding the work during the forward stroke of the knife.
- 30 10. In a machine of the class described, a knife reciprocating in the line of feed of the work and arranged to cut upon its backward stroke, means for advancing the work during the backward stroke of the knife, 35 and a presser member having its lower face shaped to enable it to slide freely over the surface of the work during the cutting stroke of the knife to gage the depth of cut made by the knife and to bite into the work upon 40 the non-cutting stroke of the knife to feed the work with the knife.
11. In a machine of the class described, a knife reciprocating in the line of feed of the work and arranged to cut upon its backward 45 stroke, a reciprocating feed dog for advancing the work during the backward stroke of the knife, and a reciprocating presser foot constructed and arranged to advance the work during the forward stroke of the knife 50 and to gage the relation of the knife to the work during the backward stroke of the knife.
12. In a machine of the class described, a knife reciprocating in the line of feed of the work and arranged to cut upon its backward stroke, and alternately operated feed devices for advancing the work during both the backward and forward strokes of the knife, one of said devices operating to gage 55 the depth of the cut in the work.
13. In a machine of the class described, feeding means intermittently operative to feed the work, cutting means movable opposite to the direction of feed to form a lip 60 on the work while said feeding means is operative and to displace the lip relatively to the work as it is formed, said means being movable to its starting position while said feeding means is inoperative, and means for engaging the displaced lip to impart 70 an additional feed movement to the work while said cutting means is returning to starting position.
14. In a machine of the class described, a knife reciprocating in the line of feed of the work and arranged to cut upon its backward stroke to form a lip and to displace the lip laterally as it is formed, means for advancing the work during the backward stroke of the knife, and means movable with 75 the knife for engaging the displaced portion of the lip to feed the work during the forward stroke of the knife.
15. In a machine of the character described, a main feeding device intermittently 80 operative to feed the work, and means constantly in engagement with the work for making a cut of a predetermined depth in the work while the work is being fed by said device and for imparting additional feed 85 movements to the work while said device is inoperative.
16. In a machine of the class described, a knife reciprocating in the line of feed of the work and arranged to cut upon its backward stroke, a feed device for advancing the work with the knife during the forward stroke of the knife, a four-motion feed dog for feeding the work against the knife while the knife is moving opposite to the direction of feed to cut the work, and means for operating the feed dog to feed the work through a greater distance than it is fed by 90 said feed device.
17. In a machine of the class described, a pair of knife carriers, means for simultaneously reciprocating said carriers in unison in lines parallel with the direction of work feed, a channeling knife attached to one of said carriers, an edge slitting knife attached to the other carrier, said knives being arranged to 95 cut upon their backward strokes, a four-motion feed dog for advancing the work while said knives are moving in the opposite direction to cut the work, and a presser foot associated with each knife constructed and arranged to slide freely over the surface of the work during the backward strokes of the knives to gage the depth of the cut and 100 to bite into the work to feed it with the knives during the forward strokes of the knives.
18. In a machine of the class described, two reciprocating slides, mechanism for actuating said slides simultaneously in opposite directions, a feed device on one slide effective during the forward movement of said slide to feed the work, a knife on the other slide effective on the backward stroke 105 of the latter to cut the work, and a presser 110
- 130

- foot on the knife slide for gaging the depth of the cut in the work and for feeding the work during the forward stroke of said slide.
- 5 19. In a machine of the class described, two horizontally reciprocating slides, mechanism for actuating said slides simultaneously in opposite directions, a feed device on one slide effective during the forward movement of said slide to feed the work, two vertically movable carriers on the other slide, a channeling knife on one carrier, an edge slitting knife on the other carrier, said knives being arranged to cut the work when the knife-carrier slide is moved backwardly, and means on the knife-carrier slide for imparting an auxiliary feed movement to the work while the knife is moving forwardly.
- 10 20. In a machine of the class described, feeding means intermittently operative to feed the work, cutting means movable opposite to the direction of feed to cut the work while said feeding means is operative and movable to starting position while said feeding means is inoperative, means for imparting an additional feed movement to the work during the movement of the cutting means to starting position, and means for varying the length of the feed movements imparted by said feed members.
- 15 21. In a machine of the class described, feeding means intermittently operative to feed the work, cutting means movable opposite to the direction of feed to cut the work while said feeding means is operative and movable to starting position while said feeding means is inoperative, means for imparting an additional feed movement to the work during the movement of the cutting means to starting position, and means operative while the machine is running for varying the length of the feed movements imparted to the work by said feed members.
- 20 22. In a machine of the class described, a knife reciprocating in the line of feed of the work and arranged to cut upon its backward stroke, alternately operated feed members, one for advancing the work during the backward stroke of the knife and the other for advancing the work during the forward stroke of the knife, and means for simultaneously varying the length of the feed movements imparted by said feed members.
- 25 23. In a machine of the class described, a knife reciprocating in the line of feed of the work and arranged to cut upon its backward stroke, alternately operated feed members, one for advancing the work during the backward stroke of the knife and the other for advancing the work during the forward stroke of the knife, and means for varying proportionately the length of the feed movements imparted by said feed members.
- 30 24. In a machine of the class described, a knife reciprocating in the line of feed of the work and arranged to cut upon its backward stroke, alternately operated feed devices, one for advancing the work during the backward stroke of the knife and the other for advancing the work during the forward stroke of the knife, and means for varying the length of the feed movements imparted by each of said feed devices.
- 35 25. In a machine of the class described, a reciprocating feed device effective upon its forward stroke to feed the work, a reciprocating knife effective upon its backward stroke to cut the work, means for moving the feed device forward to feed the work and for moving the knife backward to cut the work continuously throughout the feed of the work, and means operative while the machine is running for varying both the length of stroke of the feed device and the length of stroke of the knife.
- 40 26. In a machine of the class described, a reciprocating feed device effective upon its forward stroke to feed the work, a reciprocating knife effective upon its backward stroke to cut the work, means for moving the feed device and the knife simultaneously in opposite directions throughout the duration of each feed stroke, and adjustable means for varying proportionately the length of stroke of the feed device and the length of stroke of the knife.
- 45 27. In a machine of the class described, a knife adapted to reciprocate in the line of feed of the work and to cut upon its backward stroke, a reciprocating feed device for feeding the work against the knife while the knife is moving backwardly to cut the work, means for moving the knife backwardly throughout the feed of the work, an adjustable device for varying the length of stroke of said knife, an adjustable device for varying the length of stroke of said feed device, and means under the control of the operator for simultaneously adjusting said devices.
- 50 28. In a machine of the class described, feeding means intermittently operative to feed the work, cutting means movable opposite to the direction of feed to cut the work while said feeding means is operative and movable to its starting position while said feeding means is inoperative, an actuator having a constant throw for imparting movement to the feeding means, a second actuator having a constant throw for imparting movement to the cutting means, and adjustable devices for transmitting more or less of the throw of each actuator to the means respectively operated thereby.
- 55 29. In a machine of the class described, a knife reciprocating in the line of feed of the work and arranged to cut upon its backward stroke, a reciprocating main feed device for feeding the work against the knife while the knife is moving backwardly to cut

the work, a reciprocatory auxiliary feed device for feeding the work with the knife during the forward stroke of the latter, and means for varying the length of stroke of 5 said knife and of said main and auxiliary feed devices.

30. In a machine of the class described, cutting means, a four-motion feed dog movable relatively to the cutting means for feeding 10 the work to the cutting means, means for imparting forward and backward movements to the feed dog, an actuator for imparting upward and downward movements to the feed dog, and means for arresting the 15 downward movement of the feed dog to render it ineffective to feed the work.

31. In a machine of the class described, cutting means, a four-motion feed dog movable relatively to the cutting means for feeding 20 the work to the cutting means, means for imparting forward and backward movements to the feed dog, an actuator for imparting upward and downward movements to the feed dog, yieldable connections between 25 said actuator and the feed dog normally effective to transmit in full the throw of the actuator to the feed dog, and means for arresting the downward movement of the feed dog at different points in its stroke.

30. 32. In a machine of the class described, a pair of knives arranged to reciprocate in the line of feed of the work and to cut upon their backward strokes, means for operating the knives in unison, means for feeding the 35 work against the knives while they are moving backwardly, and an auxiliary feed device associated with each knife for feeding the work with the knives while they are moving forwardly.

40. 33. In a machine of the class described, a pair of knives arranged to reciprocate in the line of feed of the work and to cut upon their backward strokes, means for operating the knives in unison, means for feeding the 45 work against the knives while they are moving backwardly, and an auxiliary feed device associated with each knife for feeding the work with the knives while they are moving forwardly and for gaging the relation of the 50 work to the knives.

34. In a machine of the class described, a reciprocatory slide, a guideway in one face of the slide extending transversely of the direction of movement of the slide, a knife, 55 and a knife carrier movable in said guideway, the slide and the knife carrier having respectively interengaging groove-and-tongue connections extending lengthwise of said guideway and arranged to retain the carrier 60 against lateral displacement in said guideway.

35. In a machine of the class described, a reciprocatory slide, a guideway in one face of the slide extending transversely of the direction of movement of the slide, a knife, 65

a knife carrier movable in said guideway, the slide and the knife carrier having respectively interengaging groove-and-tongue connections extending lengthwise of said guideway and arranged to retain the carrier 70 against lateral displacement in said guideway, said slide and said tongue being cut away to provide respectively an aperture and a notch arranged in registration with one another, and an actuator projecting 75 through said aperture and into said notch for moving said carrier in said guideway.

36. In a machine of the class described, a pair of parallel slides arranged side-by-side in sliding contact, means for reciprocating 80 said slides arranged to move them simultaneously in opposite directions, guideways in the contiguous faces of said slides, each of said guideways having a longitudinal groove in one side thereof, a knife, a knife carrier 85 movable in one of said guideways, a feed dog, a feed dog carrier movable in the other of said guideways, and lateral tongues on said carriers slidably interengaging with the grooves in the respective guideways. 90

37. In a machine of the class described, a channeling knife, an edge slitting knife, means for reciprocating said knives in unison in the line of feed to form an inner and an outer lip on a sole, means for feeding the sole 95 against the cutting edges of the knives while the knives are moving opposite to the direction of feed, and a presser foot associated with said knives for gaging the depth to which the knives penetrate the sole stock, said presser foot being effective to continue the feed of the sole while the knives are moving in the direction of feed. 100

38. In a machine of the class described, feeding means, intermittently operative to feed the work, and a vertically yieldable and horizontally reciprocable unit comprising a knife and presser foot movable opposite to the direction of feed to make a cut of a predetermined depth in the work while said feeding means is operative, and movable in the direction of feed while said feeding means is inoperative to impart an additional feed movement to the work without cutting the work. 115

39. In a machine of the class described, a work support, means for feeding the work across said support, a lip-forming knife, a chamfer knife, means for supporting said knives for movement into and out of the path of the work, and a member connected with each of said knives and operable to withdraw them simultaneously from the path of the work. 120

40. In a machine of the class described, vertically movable channel and edge knives, a horizontally movable chamfer knife, means normally operative to maintain all of said knives yieldingly in the path of the work, mechanism for raising the channel and edge 125 130

knives from the path of the work, and means connected with said mechanism for withdrawing the chamfer knife from the path of the work concurrently with the raising of 5 the channel and edge knives.

41. In a machine of the class described, means for feeding and cutting the work, an edge gage for positioning the work relatively to the cutting means, a chamfer knife located at one side of the edge gage and movable relatively thereto transversely of the direction of work feed, means for yieldingly holding the chamfer knife in the path of the work, and a gage movable with the chamfer 10 knife and adapted to be engaged by the work to determine the relation of said knife to the work.

42. In a machine of the class described, means for feeding and cutting the work, 20 an edge gage for positioning the work relatively to the cutting means, a chamfer knife located at one side of the edge gage and movable relatively thereto transversely of the direction of work feed, means for yieldingly holding the chamfer knife in the path 25 of the work, a gage movable with the chamfer knife and adapted to be engaged by the work to determine the relation of said knife to the work, and means for withdrawing 30 said chamfer knife and gage from the path of the work.

43. In a machine of the class described, means for feeding the work, a slide movable transversely of the direction of work feed, a 35 knife secured to said slide and having an inclined cutting edge for beveling the edge of the work, means for yieldingly holding the slide with said cutting edge in the path of the work, an edge gage movably mounted 40 on said slide, and means normally operative to adjust and hold said gage in a predetermined relation to said cutting edge and capable of being manipulated to permit movement of said gage relatively to said cutting edge to render the latter accessible for 45 sharpening.

44. In a machine of the class described, work feeding means, a vertically movable channeling knife normally located in the 50 path of the work, a chamfer knife movable at right angles to the direction of work feed and yieldingly held in the path of the work, and interconnected mechanisms for simultaneously withdrawing the channeling knife 55 and the chamfer knife from the path of the work.

45. In a machine of the class described, a work table, means for feeding and cutting the work, an edge gage carried by the work 60 table for positioning the work relatively to the cutting means, a slide movable toward and from the work table, a fixed guideway for said slide, a chamfer knife carried by said slide, and means for adjusting the work 65 table transversely of the direction of work

feed to vary the operative position of the edge gage and for imparting additional movement to the work table to facilitate the removal of the chamfer knife slide from said guideway. 70

46. In a machine of the class described, a feed device movable through an orbital path for feeding the work, a knife reciprocating in the line of feed and effective upon its backward stroke to cut the work, means for 75 operating the feed device and the knife to feed and cut the work simultaneously, and means for varying the length of stroke of the knife, the extent of the component of movement of the feed device in the direction 80 of work feed, and the extent of the component of movement of the feed device in a direction at right angles to the direction of work feed.

47. In a machine of the class described, a 85 four-motion feed device movable through an orbital path for feeding the work, a knife reciprocating in the line of feed and effective upon its backward stroke to cut the work, and means for simultaneously shortening 90 the stroke of the knife, the movements of the feed device, in the direction of work feed, and the extent of the component of movements of the feed device toward and from the work. 95

48. In a machine of the class described, a feed dog, mechanism for imparting a four-way motion to the feed dog including an actuator for raising and lowering the feed dog, a stop to limit the downward movement of the feed dog, and means for moving said stop while the machine is running to render ineffective to a greater or less degree the throw of said actuator. 100

49. In a machine of the class described, a work table, a reciprocating slide, a shaft, operative connections between said shaft and said slide, a feed dog movable through a substantially elliptical orbit having its longest diameter substantially horizontal, a reciprocating carrier for the feed dog comprising a yielding member to which the feed dog is secured, a member reciprocated by said shaft, a spring interposed between said members and tending to separate them, means connecting said members to limit their separation, said means being adjustable to shift said diameter toward or from the work table, and an abutment in the path of said yielding member to determine the lower limit of 110 movement of the feed dog. 115

50. In a machine of the class described, a work table, a reciprocating slide, a shaft, operative connections between said shaft and said slide, a feed dog, a reciprocating carrier 125 for the feed dog comprising a yielding member to which the feed dog is secured, an abutment in the path of said member to limit its movement toward the work table, and means for adjusting said abutment while 130

the machine is running to prevent the feed dog from engaging the work.

51. In a machine of the class described, a four-motion feed dog having a forward movement for feeding the work, an auxiliary feed device for advancing the work between successive forward movements of the feed dog, and means for operating the feed dog and the auxiliary feed device constructed and arranged to move the feed dog forwardly through a greater distance than the work is fed by the auxiliary feed device.

52. In a machine of the class described, a four-motion feed dog having a forward movement for feeding the work, an auxiliary feed device for advancing the work between successive forward movements of the feed dog, means for operating the feed dog and the auxiliary feed device constructed and arranged to move the feed dog forwardly through a greater distance than the work is fed by the auxiliary feed device, and means for varying the relation between the path of the feed dog and the path of the work so that the desired length of feed movement may be derived from the feed dog regardless of variations in the thickness or density of the work.

53. In a machine of the class described, a four-motion feed dog for feeding the work, and means for independently varying the upper and lower limits of movement of the feed dog.

54. In a machine of the class described, a work support, a feed dog having an orbital movement for feeding the work across said support, means for varying the extent of the vertical component of movement of the feed dog, and other means adjustable to vary the lower limit of said movement of the feed dog.

55. In a machine of the class described, a frame, two slides mounted in abutting side-by-side relation for independent reciprocatory movements in parallel planes, one of said slides having a guideway in its inner face and having a groove opening into said guideway and extending lengthwise thereof, a knife carrier movable in said guideway in sliding engagement with the inner face of the other slide, a tongue on the first slide fitted to slide within said groove to retain the knife carrier against lateral displacement in said guideway, and a knife mounted on said carrier.

56. In a machine of the class described, means for feeding and channeling a sole, an edge gage for positioning the work relatively to the cutting means, and means movable relatively to the edge gage in a direction substantially perpendicular to the direction of work feed for beveling the edge of the sole.

57. In a machine of the class described, means for feeding and cutting the work, an edge gage for positioning the work rela-

tively to the cutting means, a chamfer knife movable relatively to the edge gage in a direction substantially perpendicular to the direction of work feed, yielding means for urging the chamfer knife toward the work, and a gage movable in unison with the chamfer knife to control the position thereof.

58. In a machine of the class described, a main feed device intermittently operative to feed the work, cutting means movable opposite to the direction of feed to cut the work while said feed device is operative and movable to starting position while said feeding means is inoperative, an auxiliary feed device for imparting an additional feed movement to the work during the movement of the cutting means to starting position, means for proportionally adjusting the length of strokes of the main and auxiliary feed devices, and means for varying the length of stroke of one of said feed devices independently of the other of said feed devices.

59. In a machine of the class described, a reciprocating feed device effective upon its forward stroke to feed the work, a reciprocating knife effective upon its backward stroke to cut the work while said feed device is inoperative and movable to starting position while said feed device is inoperative, other means for imparting an additional feed movement to the work during the movement of the knife to starting position, means for moving said feed device and the knife simultaneously in opposite directions for varying proportionately the length of stroke of the feed device and the length of stroke of the knife, and means for varying the length of stroke of said feed device independently of the length of stroke of the knife.

60. In a machine of the class described, a knife reciprocating in the line of feed of the work and arranged to cut upon its backward stroke, a presser foot for feeding the work at a definite rate of speed during the forward stroke of the knife, and means for feeding the work at a greater rate of speed during the backward stroke of the knife.

61. In a machine of the class described, a support for a piece of work to be fed through the machine, a knife reciprocating in the line of feed of the work and arranged to cut upon its backward stroke, a feed dog movable through an orbital path elongated in the direction of work feed for advancing the work during the backward stroke of the knife, means for feeding the work during the forward stroke of the knife, and means for shifting the longest diameter of said path toward or from the work support.

In testimony whereof I have signed my name to this specification.

HARRIE A. BALLARD.
